PACKAGING CONTAINER FOR A PIE OR THE LIKE

James N. Cannell, % The Quality Bakery, 50 N.
Glenwood Ave., Columbus, Ohio 43222

Filed Feb. 17, 1971, Ser. No. 116,304

Term of patent 14 years

Int. Cl. D9—03

U.S. Cl. D9—220

FIG. 1

FIG. 2

FIG. 3

FIG. 4

FIG. 1 is an elevational view of a packaging container for a pie or the like embodying my new design;

FIG. 2 is a top plan view;

FIG. 3 is a bottom plan view; and

FIG. 4 is an enlarged fragmentary vertical sectional view thereof taken along line 4—4 of FIG. 2.

I claim:

The ornamental design for a packaging container for a pie or the like, as shown.
